CLAIM

The ornamental design for a dispenser for chemically-coded strips used in medical treatment, as shown and described.

DESCRIPTION

FIG. 1 is a right side elevational view of a dispenser for chemically-coded strips used in medical treatment showing my new design, the left side being a mirror image of that shown;

FIG. 2 is a front elevational view thereof;

FIG. 3 is a rear elevational view thereof;

FIG. 4 is a bottom plan view thereof; and

FIG. 5 is a top plan view thereof.
